UNITED STATES PATENT OFFICE.

PERRIN G. MARCH, OF CINCINNATI, OHIO.

DRILLING-MACHINE.

SPECIFICATION forming part of Letters Patent No. 309,073, dated December 9, 1884.

Application filed February 2, 1884. (No model.)

To all whom it may concern:

Be it known that I, PERRIN G. MARCH, a citizen of the United States, and a resident of Cincinnati, in the county of Hamilton and State of Ohio, have invented certain new and useful Improvements in Drill-Presses, of which the following is a specification.

My invention relates to an improvement in drill-presses.

10 The object of my invention is to provide a table capable of being adjusted radially, angularly, and vertically under the drill-tool, enabling radial, angular, and vertical drilling to be accomplished readily on the same machine. This I accomplish by the construction and combination of devices hereinafter described and claimed, reference being made to the accompanying drawings, in which—

20 Figure 1 is a side elevation of the drill-press with my improvement attached. Fig. 2 is a sectional plan on line $x-x$, Figs. 1, 3, 4. Fig. 3 is a sectional elevation on line $y-y$, Figs. 1 and 2. Fig. 4 is a section of line $y-y$, Fig. 2. Fig. 5 is a broken elevation of one section of the 25 table arm or bracket. Fig. 6 is a broken sectional elevation on the two sections of the table-arm on line $x'-x'$, Fig. 2.

A represents the base, B the pillar or column, C the drill-spindle, and D D' E E', driving pulleys and gear, of an ordinary drill-press. A vertical rack-bar, F, is arranged loosely at the side of the pillar B, its lower end being supported by an annular shoulder, a', at the base of the pillar. The sectional arm carrying the work 35 supporting the table is indicated at G G'. The inner section, G, is provided with a housing or box, g, in which is journaled the pinion b, the rack F engaging said pinion and passing through the housing g between the pillar and the pinion.

40 Section G' is attached to the section G, as follows:

c d represent disks cast on and with the sections G' G, respectively, through which 45 passes the axis H, forming the journal on which the section G' may be turned for adjustment.

In order to prevent any lateral motion of the table supported on the section G', I provide an annular groove-bearing, e i, formed on the periphery of the disks c d, as shown in Figs. 2, 50 and 6.

I represents a circular T-groove formed in the face of disk d, to receive a fastening-bolt, J, which passes through a hole in disk e, to which it is secured by a nut, j.

55

K represents an opening in the circular groove I, for the insertion of the head J' of bolt J into said circular groove.

When it is desired to move the section G', nut j is loosened so that the bolt will move 60 with the disk e around in the T-slot. The section G' is made hollow or open for the purpose of lightness, as well as enabling the screws or nuts to be turned.

L represents a key or pin passed through 65 the flange e.

k represents a series of holes pierced in the shoulder i of disk e.

The lines M represent gage-marks, which are used to indicate angles for adjusting the 70 table. The pin L enters one of these holes k and holds the table momentarily until the operator can tighten the nut to secure it rigidly in position. These features may, however, be dispensed with and a set-screw employed 75 for that purpose.

O represents a table, which is secured upon the top of section G' in any desired manner. Whenever the table O is adjusted at an angle to the horizon, the center of the table is moved 80 away from the vertical plane of the drill-spindle. The inner arm-section, G, is divided at its rear, as at R, and the divisions are connected by a bolt and nut, R', (see Fig. 2,) in such manner that by loosening the nut the said arm-section can be rotated radially or in a direction around the pillar B, and in such movement it will carry with it the loosely-supported 85 rack-bar F. When the required radial adjustment is obtained, the nut is tightened up, 90 thereby clamping the inner arm-section on the pillar. In this way the sectional arm can be adjusted in a direction around the pillar to adjust the center of the work-supporting table into or out of the vertical plane of the drill-spindle.

95 The vertical adjustment of the sectional arm is likewise made by loosening the nut and bolt R' and rotating the pinion b in the proper direction, after which the nut is tightened up to clamp the inner arm-section 100 in its adjusted position on the pillar.

I may employ gearing to adjust the outer

arm-section, G', angularly from a horizontal plane, in which event the pin L and holes k may be dispensed with.

I do not broadly claim a work-supporting table arranged beneath a drill-spindle and capable of vertical movement, an angular adjustment from a horizontal plane, and a lateral movement in a direction around the pillar carrying the drill-spindle.

10 Having thus described my invention, what I claim is—

1. The combination of a pillar for carrying a drill-spindle, the inner arm-section, G, encircling the pillar and adapted to be moved vertically and in a direction around the same, and having the circular groove I and annular bearing i, the outer arm-section, G', centrally pivoted to the other arm-section by the bolt H, and having the annular bearing e, the bolt J, connected with the outer arm-section, and having its head in the annular groove, and a work-supporting table on the outer end of the outer arm-section, G', substantially as described.

25 2. The combination, with a pillar having

the vertical rack F, of the inner arm-section, G, carrying the gear b, engaging the rack and capable of adjustment in a direction around the pillar, the outer arm-section, G', swiveled to the inner arm-section for angular adjustment from a horizontal plane, and a work-supporting table on the outer arm-section, substantially as described.

3. The combination of a pillar for carrying a drill-spindle, a rack, F, arranged vertically on the pillar, an inner arm-section, G, encircling the pillar, and having a gear, b, engaging the rack and capable of adjustment in a direction around the pillar, the outer arm-section, G', carrying a work-supporting table, the pivot-bolt H, centrally connecting the two arm-sections, and the annular groove-bearing e and i at the outer adjoining edges of the arm-sections, substantially as described.

In testimony whereof I have hereunto set my hand.

PERRIN G. MARCH.
